SPEAKER PROTECTIVE DEVICE FOR
DRIVE-IN THEATERS

Rocco Dilione, Red Bank, N. J.

Application August 16, 1950, Serial No. 179,790

10 Claims. (Cl. 20—1.12)

1

This invention relates to protective devices for the speakers in a drive-in theater and more particularly to a device that will automatically chock a car when the speaker is removed from its support to be mounted in the car and vice versa will automatically release the chocking device when the speaker is returned to its support.

In the drive-in theaters there are a plurality of supporting posts distributed throughout the area in which the cars are to be parked. These supporting posts or standards are utilized to permit a speaker to be hung or supported by the post and the necessary electrical connection from the speaker may pass through the post and in turn under ground to the central operator's control or sound distributing unit. The drive-in theaters thus must provide a large quantity of speakers over the area of their theater with a minimum of attendants and due to the fact that the attendants must work in the dark they are able to direct and position the cars entering and to see that the speakers are removed from the posts or standards and are hung over the glass of the car, but the attendants cannot anticipate the time that each car will be ready to leave and therefore the car driver is requested to return the speaker to the post or supporting standard. The average drive-in theater has found in the past that a great many drivers start their car and leave without returning the speaker to its proper post or standard and thus with the speaker still mounted in the car the wire from said speaker is torn loose from the post or standard. This is a great loss to the drive-in theater as the average driver becomes alarmed and would rather make his escape than report the damage or return the speaker.

It is an object of this invention to provide a device that is connected to the speaker supporting standard and in which the device will automatically chock the car when the speaker is removed from said standard.

A further object of this invention is to provide a theft preventive means for speakers in a drive-in theater in which said means prevents the movement of the car to leave the drive-in theater unless the speaker is returned to its proper designated supporting means.

A still further object of this invention is to provide a mechanically operated trigger device to support a speaker for a drive-in theater in which the trigger device is connected to a mechanically operated chocking means so that upon the removal of the speaker from its support the trigger will be released and the chocking means will be effected.

2

Other objects of this invention will be apparent upon reference to the detailed description and the drawings in which

Fig. 1 is a perspective view of the device with the chocking means partly in cross section,

Fig. 2 is a side elevational view of the chocking means in a released position,

Fig. 3 is a cross sectional view taken on the line 3—3 of Fig. 1,

Fig. 4 is a plan view taken on line 4—4 of Fig. 3,

Fig. 5 is a cross sectional view taken on the line 5—5 of Fig. 3,

Fig. 6 is a side elevational view of another embodiment of the chocking means, and

Fig. 7 is a side elevational view of the chocking means illustrated in Fig. 6 in a released position.

Referring to Fig. 1 there is illustrated a supporting post or standard 10 that may be mounted in a concrete base or any other means to the ground. The post 10 at its upper end is provided with an electrical connection box 11. Mounted in opposed relationship and affixed to the post or standard 10 are a pair of boxes or baskets 12. The baskets 12 are designed to be as small as possible yet provide sufficient space internally to completely enclose the type of speaker 14 used in a drive-in theater. The baskets 12 are provided with hinged covers 13. A hollow pipe 15 is connected from the basket 12 through the ground to a chocking unit 18. Within the pipe 15 there is a stiff control wire 16. The chocking device 18 is comprised of a box-like structure having a pair of side members 20 and 21 and a top member 22. The top member 22 extends over approximately one half the length of the side members 20 and 21 and a hinged cover member 23 is attached to the edge of the top member 22 to provide in its closed position a complete covering of the side members 20 and 21. A cam 25 is pivotally mounted by means of a pin 26 to the side 20 of the chocking device 18. The cam 25 is also provided with a pin 27 and a stop pin 28 is affixed to the side 20 so as to limit the degree of pivotal movement of the cam 25 in one direction. The pipe 15 extends into the chocking device 18 and may be clamped to one side of the chocking device by a pair of clamps 29. The wire 16 extending through the pipe 15 at its end is fastened about the pin 27 of the cam 25. The wire 16 at its opposite end is attached to the cover 13 of the basket 12. Thus it is apparent as illustrated in Fig. 1 that when the cover 13 is raised to the position illustrated, the movement of the cover 13 upward will in turn move the cam 25 to the position illustrated and the cam 25 will in turn raise the hinged cover 23 to its chocking position as

40
45
50
55

illustrated. It is to be noted that with the cam 25 in the position illustrated any attempt of the car to move forward will in turn exert pressure on the cover 23. The cover 23 being supported by cam 25 will exert all of this pressure on the cam and in the position illustrated the force would attempt to force the cam 25 against the stop pin 28. Thus the stop pin becomes the main locking member and the structural member absorbing all of this force.

Referring to Fig. 2 there is illustrated the same chocking device 18 with the cam 25 moved to its opposite position. This is accomplished after the speaker 14 has been returned to the basket 12 and the cover 13 dropped to its closed position. With the cam 25 in the position illustrated in Fig. 2 it is apparent that the cover 23 may lie in its horizontal position and in this position will offer no resistance to the passage of a car thereover.

As already described the chocking device 18 is connected by means of a cable or wire 16 to the cover 13 of the basket 12. Referring to Fig. 3 we may clearly see the manner in which the wire 16 is attached to an extension arm 30 of the cover 13. The extended arm 30 is rigidly pinned or bolted to the cover 13 and will move according to the position of the cover 13. The extended arm 30 is positioned on the right hand side of the cover 13 as more clearly illustrated in Figs. 4 and 5. The arm 30 extends into the basket 12 and becomes a locking means, that is, the means to lock the cover 13 in its open position when the speaker has been removed from the basket 12. To accomplish this locked relationship there is provided a trigger 33 also mounted within the basket 12. The trigger 33 is comprised of two arms 34 and 35 and a central portion 36 through which a pin 37 passes. The trigger 33 is also provided with a spring leaf member 38. Member 38 may be affixed to the bottom of the basket 12 but it is positioned under the arm 34 of the trigger 33 to exert an upward pressure. Referring to Fig. 5 it is apparent that with the cover 13 of the basket 12 open and the speaker 14 removed, the arm 34 of the trigger 33 will be forced upward by the spring 38. Thus arm 35 will be moved outward to abut with the side of the basket 12. It is to be noted that the end of arm 35 is provided with a 90° shelf extension 40 and with arm 35 in the position illustrated in Fig. 5, the shelf member 40 provides a barrier to prevent the downward movement of the arm 30, Fig. 3. In order that arm 30 and trigger 33 will remain in their proper relationship, there is provided an additional member 41, Figs. 3 and 4 that is retained in parallel relationship with the side of the basket 12 but retained in a spaced relationship so that the arm 30 may pass freely between the side of the basket 12 and the member 41. It is to be noted that member 41 is provided with a bent portion 42. This permits a limited degree of movement by the shelf 40 of arm 35 of the trigger 33. This limited degree of movement is sufficient to move the shelf 40 far enough to the left, Fig. 5, to permit arm 30 to pass downward without obstruction. It is to be noted further that it is necessary to place the speaker 14 in basket 12 so that the weight of the speaker 14 bears on the arm 34 of the trigger 33 and thus will move arm 34 to the dotted position illustrated and thus releases the trigger mechanism to permit the unobstructed movement of the cover 13.

It is apparent in operation that when a car is directed into a proper position in the drive-in theater the attendant may then raise the cover 13 of the basket 12 which will in turn automatically chock the front wheel of the car. The speaker is then passed into the car for use. The operator of the car is then advised that he cannot drive his car out of the parked position until he has returned the speaker 14 into the basket 12 as the chocking device remains locked until the speaker releases same and further when the operator of the car has returned the speaker 14 to the basket 12 it is apparent that the trigger 33 will be released and the cover 13 may drop by gravity and of course when the cover 13 drops the cam 25 is moved to the position illustrated in Fig. 2 and the chocking cover 23 will also drop by gravity and thus the operator may drive his car away from the parked position.

Referring to Figs. 6 and 7 there is illustrated a further embodiment of the chocking device, that is, instead of the device 18 already described there is provided a unit 50. The unit 50 may be similarly box shaped in form but as illustrated it is formed with two ends 51 and 52 and a top member 53 and is not provided with a pair of sides. A small block member 54 may be suspended from the top 53 on one side thereof. A pin 55 is mounted at approximately the center of the lower portion of block 54. A pair of U-shaped bars 56 and 57 are provided, however one side of the U-shaped member may be longer than the opposite side as the extended member becomes the end that is to be attached to the operating mechanism. Thus on the end 58 of bar 56 there is a pin 59 and on the end 60 of the bar 57 there is a pin 61. The U-shaped member 56 is pivotally supported on either side of the top member 53 by a pin 62 and the U-shaped member 57 is pivotally supported on either side of the top member 53 by a pin 63. The top portion of the bars 56 and 57 may be flat or may be slightly curved to conform with the contour of the outer periphery of a tire. With the bars 56 and 57 pivotally mounted as described they may be connected in a controlled relationship by means of three elements. A central pivotally supported arm 64 may be mounted on the pin 55 and arm 64 is provided with a pin 65 at one end and 66 at its opposite end. Two similarly constructed arms 67 and 68 are provided and both arms are provided with an elongated slot 69 at one end of the element. Arms 67 and 68 are provided with an aperture 70 at the opposite end of said arms. Arm 67 is mounted with the apertures 70 pivotally affixed to the pin 61 and the pin 66 of arm 64 is mounted through the elongated slot 69 of arm 67. Similarly arm 68 is mounted with its aperture 70 pivotally supported on the pin 59 and the pin 65 of arm 64 is mounted through the elongated slot 69 of arm 68. In addition it is to be noted that the wire 16 as in the aforementioned chocking device extends into the device 50 and at the end of wire 16 it is affixed to the pin 66. Also the pipe 15 is attached to the unit 50 in any clamping manner to retain pipe 15 in a fixed relationship.

It is apparent referring to Figs. 6 and 7 that the chocking device 50 will be similarly operated when the cover 13 of the basket 12 is opened, that is, the opening of cover 13 will pull wire 16 to the left, Fig. 6, thus moving arm 64 into the position as illustrated in Fig. 6. It is further apparent that with arm 64 in a vertical position, arms 67 and 68 will be pulled into the position illustrated

and they will in turn pivotally move the stop bars 56 and 57 into the position illustrated. Of course the device should not be actuated until the car has been parked in the designated position. With the car in this position as illustrated and the device locked as illustrated, the car cannot move forward or backward. To assist in providing a better leverage for arms 56 and 57, there are provided cross braces 71 which act as stop members for the arms 56 and 57 and they will take most of the stress that may be exerted by a car wheel pressing against either bar 56 or 57. Referring to Fig. 7 it is apparent that when the operator of the car has returned the speaker 14 to the basket 12, the cover 13 will drop, thus by means of wire 16 arm 64 will be moved to the position illustrated in Fig. 7. With arm 64 in this position, arms 67 and 68 are free to move outward. In the event the car wheel may be pressing against bar 57 the release of the chocking unit permits bar 56 to drop by gravity and the operator may then back his car sufficiently to permit bar 57 to drop to the dotted position illustrated. The operator may then drive away from the parked position. The elongated slots 69 in arms 67 and 68 permit this loose relationship of arms 56 and 57, that is, the arms may be held in their upward position if the car tire obstructs their downward movement, but in no case would both arms be retained in an upright position. They will either both drop out of the way or one will drop and as soon as the car is moved to other arm will also drop and there is no further obstruction to the movement of the car.

Although we have shown a single type of supporting arrangement for the speaker, we may vary the manner of supporting the speaker without departing from the spirit of this invention and although we have illustrated two forms of chocking devices that are connected and operated by a trigger mechanism that is operated by the speaker, we may vary the means of chocking in its form or in its manner of operation without departing from the spirit of this invention and this invention shall be limited only by the appended claims.

What is claimed is:

1. The combination of a speaker, a rigid support having a basket mounted thereon to retain said speaker, said basket provided with a hinged cover and being spaced above the ground so as to be accessible by an occupant of an automobile, a chocking means located on the ground remotely from said support, said chocking means being below ground level and being pivotally supported to be raised above ground level into position to be engaged by a wheel, a steel wire connecting said chocking means and said cover of said basket and being moveable on the elevation of said cover to elevate said chocking means into wheel engaging position.

2. The combination of a speaker, a speaker supporting means and a car chocking means, a rigid support having a basket mounted thereon to retain said speaker, said basket provided with a hinged cover, said chocking means provided with a pivotally supported cam and located remotely from said support, said chocking means being pivotally supported, said cam locking said chocking means in a chocking position, said chocking means and said speaker supporting means connected by means of a flexible cable in which a stiff wire is moveably supported, said cover of said basket connected to one end of said wire in said flexible cable and the other end of said wire con-

nected to said pivotally supported cam of said chocking means.

3. In a device according to claim 2, a resiliently supported trigger mounted within said basket to support said speaker, said trigger retained in an inoperative position by the weight of said speaker when said speaker bears upon said trigger, said trigger provided with an extension that is moved to either of two positions with the movement of said trigger, said extension in one position locking said basket cover in an open position when said speaker is removed from said basket, said extension in the other position releasing said basket cover when said speaker is reinserted within said basket to bear on said trigger, said cover of said basket locking said chocking means in a chocking position when said cover is in an open position.

4. The combination of a plurality of speakers, a speaker supporting means and a plurality of car chocking means, a rigid support having a plurality of baskets mounted thereon to retain said speakers, each basket provided with a hinged cover, each of said chocking means provided with a pivotally supported cam to hold said chocking means and located remotely from said support, each chocking means pivotally supported, said cam in one position locking said chocking means in a chocking position said cam in its other position releasing said chocking means to a closed position, each said chocking means and one of said speaker supporting means connected by means of a stiff wire that is moveably supported in a flexible cable, said cover of said basket connected to one end of said wire and the other end of said wire connected to said pivotally supported cam of said chocking means, means to lock each chocking means in a chocking position when said connected cover of said speaker supporting basket is elevated.

5. In a device according to claim 4, a resiliently supported trigger mounted in each basket to support said speaker, said trigger retained in an inoperative position by the weight of said speaker when said speaker bears upon said trigger, said trigger provided with an extension that is moved to either of two positions with the movement of said trigger, said extension in one position locking said basket cover in an open position when said speaker is removed from said basket, said extension in the other position releasing said basket cover when said speaker is reinserted within said basket to bear on said trigger, said cover of said basket locking said chocking means in a chocking position when said cover is in an open position.

6. The combination of a speaker, a speaker supporting means and a car chocking means, a rigid support having a basket mounted thereon to retain said speaker, said basket provided with a hinged cover, said chocking means connected to said cover of said basket by a stiff wire that is moveably supported within a flexible cable, said cover provided with a locking arm, said basket provided with a pivotally supported trigger that is biased to a locking position, said trigger provided with an extended releasing arm upon which said speaker may rest when inserted in said basket, said trigger provided with an extended arm to bear against said locking arm of said cover when said trigger is in a released position, a chocking means located upon the ground remotely from said support, said chocking means comprised of a hinged member and pivotally sup-

ported cam, said cam in one position supporting said hinged member in a chocking position.

7. In a device according to claim 6, a stop pin in said chocking device positioned adjacent to said cam to limit the pivotal movement of said cam in one direction, means to transfer the force exerted on said chocking means through said cam to said stop pin.

8. The combination of a speaker, a speaker supporting means and a car chocking means, a rigid support having a basket mounted thereon to retain said speaker, said basket provided with a hinged cover, a chocking means located on the ground remotely from said support, said chocking means comprised of a pair of hinged members that may be raised above ground level, a control arm centrally positioned between said hinged members and moveable to either of two positions, each of said hinged members connected by a link below ground level to one end of said centrally positioned control arm, a stiff wire connecting said central control arm of said chocking means and said cover of said basket, means to lock the cover of said basket and said chocking means in a chocking position when said cover is in an open position.

9. In a device according to claim 8 a spring supported trigger mounted within said basket, said spring and trigger supporting said speaker, said trigger retained in an inoperative position with said speaker bearing upon said trigger, said trigger provided with an extension to lock said

5 basket cover in an open position when said speaker is removed from said basket, said trigger releasing said basket cover when said speaker is reinserted within said basket to bear on said trigger, means to lock said cover of said basket and said chocking means in a chocking position when said cover is in an open position.

10 10 15 20 25 30 The combination of a speaker, a speaker supporting means and a car chocking means, a rigid support having a basket mounted thereon to retain said speaker, said basket provided with a hinged cover, a chocking means located on the ground remotely from said support, said chocking means pivotally supported to be raised above ground level, a cam to support and lock said chocking means in a chocking position, a stiff wire connecting said chocking means and said speaker supporting means, said cover of said basket connected to one end of said stiff wire and the other end of said stiff wire connected to said pivotally supported chocking means, said cover of said speaker supporting basket locking said chocking means in a chocking position when said cover is elevated to remove said speaker.
